Harold G. Sydenham, United States Army, Fort Benning, Ga., Henry W. Clowe, Army of the United States, Pittsburgh, Pa., and Arthur E. Du Bois, Washington, D. C.

Application September 22, 1942, Serial No. 108,310

Term of patent 3½ years

To all whom it may concern:

Be it known that we, Harold G. Sydenham, United States Army, Henry W. Clowe, Army of the United States, and Arthur E. Du Bois, citizens of the United States, residing at Fort Benning, Georgia, Pittsburgh, Pennsylvania, and Washington D. C., respectively, have invented a new, original, and ornamental Design for a Protective Cover for Soldiers or the like, of which the following is a specification, reference being had to the accompanying drawing, forming part thereof.

Fig. 1 is a perspective view of the protective cover for soldiers or the like, showing one side.

Fig. 2 is a front view of the cover.

Fig. 3 is a view of the cover in its flat condition showing the side not shown in Fig. 1.

We claim:

The ornamental design for a protective cover for soldiers or the like, as shown.

HAROLD G. SYDENHAM.
HENRY W. CLOWE.
ARTHUR E. DU BOIS.
